UNITED STATES PATENT OFFICE.

WILLIAM OTHO REID, OF STRAWN, TEXAS.

GASOLENE-CUT-OFF LOCK FOR AUTOMOBILES.

1,159,089.

Specification of Letters Patent.

Patented Nov. 2, 1915.

Application filed January 23, 1915. Serial No. 4,012.

To all whom it may concern:

Be it known that I, WILLIAM OTHO REID, a citizen of the United States, residing at Strawn, in the county of Palo Pinto and State of Texas, have invented certain new and useful Improvements in Gasolene-Cut-Off Locks for Automobiles, of which the following is a specification.

The present invention relates to a gasolene cut-off for internal combustion engines and has for its object to provide a device of this character which embodies novel features of construction whereby it can be readily applied to any conventional construction of automobile and will provide a lock controlled means for cutting off the supply of gasolene to the carbureter so that the car can be left standing without danger of being stolen or used by unauthorized persons.

Further objects of the invention are to provide a device of this character which is simple and inexpensive in its construction, which will automatically cut off the flow of gasolene to the carbureter if any effort is made to tamper with the same, which can be easily and quickly locked in either an open or a closed position, and which will render it impossible for the car to be used or stolen when the cut-off is locked in operative position.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which—

Figure 1 is a transverse sectional view through a gasolene tank provided with a cut-off constructed in accordance with the invention, portions of the seat under which the tank is mounted also being shown. Fig. 2 is an enlarged detail view of the bell crank connection between the locking rod and the plunger at the top of the tank. Fig. 3 is an enlarged detail view of the valve mechanism mounted within the sediment bulb, the valve being shown in a closed position by full lines and in an open position by dotted lines. Fig. 4 is an enlarged detail view illustrating the manner in which the lock engages the locking rod to hold the latter against sliding movement. Fig. 5 is a front elevation

of a suitable form of lock adapted to be used in connection with the invention.

Corresponding and like parts are referred to in the following description and indicated in all the views of the drawing by the same reference characters.

Specifically describing the present embodiment of the invention, the numeral 1 designates the gasolene tank which may be of any conventional construction and which is shown as mounted in the usual manner under a seat 2. A sediment bulb 3 is provided at the bottom of the tank 1 and a gasolene supply pipe 4 communicates with one side of the sediment bulb, said supply pipe serving to convey gasolene from the tank to the carbureter. The usual drain cock 5 is applied to the bottom of the sediment bulb.

A valve 6 is provided for closing the end of the supply pipe 4, said valve being carried by an arm 7 which is pivoted at 8 upon a pair of ears projecting inwardly from one side of the sediment bulb. A rearwardly projecting lever 9 is rigidly connected with the arm 7 at the pivot end thereof and constitutes a means for swinging the arm to move the valve toward or away from its seat. The free end of the lever 9 is loosely connected by an upright link 10 to a slide 11 which is mounted upon an upright guide rod 12 projecting from the bottom of the sediment bulb. A coil spring 13 surrounds the guide rod 12 and is interposed between the bottom of the sediment bulb and the slide 11 so as to normally move the slide upwardly and swing the valve 6 into a closed position, thereby cutting off the flow of gasolene and rendering it impossible to start the engine. The upper end of the guide rod 12 terminates in a head 14 which is loosely received within a cage 15 at the lower end of an upright push rod 16, the upper end of the said push rod being provided with a socket 17 which loosely receives the lower end of a plunger 18. The upper end of the plunger 18 extends through a suitable packing box 19 at the top of the tank 1 and in the present instance the lower end of the plunger is offset laterally since the socket 17 and packing box 19 are slightly out of alignment with each other.

The upper extremity of the plunger 18 has a pin and slot connection with one arm of an upright bell crank lever 21 which is pivotally mounted upon a bracket 22 pro-

jecting from the top of the tank 1. The opposite arm of the bell crank lever 21 is connected to a horizontally disposed locking slide 23 which passes through a suitable guide opening in the front 2^a of the seat 2. With this construction it will be obvious that by sliding the locking rod 23 back and forth motion can be transmitted through the bell crank lever 21 to the plunger 18 so as to reciprocate the latter up and down. When the plunger is pushed down the cage 15 at the lower end of the push rod 16 engages the slide 11 and moves the same against the action of the spring 13 so as to open the cut-off valve 6. On the other hand, when the plunger 18 is moved upwardly the action of the spring 13 will also move the slide 11 and push rod 16 upwardly so as to result in closing the cut-off valve 6.

The forward end of the locking rod 23 is provided with a pair of spaced notches 24 and 25 adapted to be engaged by the tongue 26 of a suitable cabinet lock 27 which is mounted in the front 2^a of the seat. When the locking rod 23 is pulled outwardly and the tongue 26 of the lock caused to engage the notch 24 thereof, as indicated by Fig. 1, the cut-off valve 6 is held in a closed position by means of the spring 13, thereby preventing gasoline from flowing through the supply pipe 4 and rendering it impossible for the engine to be started. When the cut-off is thus locked in a closed position the car may be left standing with absolutely no danger of being stolen or used by an unauthorized person. When it is desired to use the car, the locking rod 23 is pushed inwardly and the tongue 26 of the lock caused to engage the outer notch 25 of the locking rod. The plunger 18 and push rod 16 are thereby forced downwardly so as to move the slide 11 against the action of the spring 13 and open the cut-off valve. Gasoline can then flow freely through the supply pipe so that the engine can be started and the car used in the usual manner.

Any suitable form of cabinet lock can be utilized for engaging the notches of the locking rod 23 to hold the cut-off securely in either an open or a closed position, and when leaving the car the operator can very quickly lock the cut-off in a closed position so as to render it impossible for any person to start the engine and use the car. Attention is also directed to the fact that the plunger 18 fits loosely within the socket 17 of the push rod 16 so that should any effort be made to tamper with the cut-off mechanism by destroying the portions thereof mounted upon the exterior of the tank and withdrawing the plunger 18, the only result will be to disengage the plunger from the push rod so that the latter will fall over to one side and the cut-off valve will be closed by the action of the spring 13. This

would leave the car dead until after the gasoline was drawn off and the parts of the cut-off mechanism properly connected up again. It will thus be obvious that by forming the connecting link between the bell 70 crank lever 21 and the slide 11 in two parts as illustrated upon the drawing effective provision is made against successful tampering with the cut-off mechanism by any person attempting to steal or make unauthorized use of the car.

Having thus described the invention, what I claim as new and desire to secure by Letters Patent, is:

1. In a gasoline cut-off for internal combustion engines, the combination of a gasoline tank, a feed pipe leading therefrom, a valve for closing the feed pipe, a guide rod, a slide mounted upon the guide rod and having an operative connection with the 85 valve, a spring engaging the slide and normally holding the valve in a closed position, a plunger extending through the gasoline tank, an operative connection between the plunger and the slide, and means for operating the plunger.

2. In a gasoline cut-off for internal combustion engines, the combination of a gasoline tank, a gasoline feed pipe leading therefrom, a valve for controlling the flow 95 through the gasoline feed pipe, a guide rod, a slide mounted upon the guide rod and having an operative connection with the valve, a spring surrounding the guide rod and engaging the slide to hold the valve normally 100 in a closed position, a push rod slidably engaging the guide rod and adapted to move the slide against the action of the spring to open the valve, a plunger extending through the tank and having an operative 105 connection with the push rod, and means for actuating the plunger.

3. In a gasoline cut-off for internal combustion engines, the combination of a gasoline tank, a gasoline feed pipe leading therefrom, a valve for controlling the flow of gasoline through the feed pipe, a guide rod, a slide mounted upon the guide rod and having an operative connection with the valve, a spring surrounding the guide rod and engaging the slide to hold the valve normally 110 in a closed position, a push rod provided at its upper end with a socket and at its lower end with a cage loosely engaging the guide rod and adapted to engage the 115 slide to move the same against the action of the spring and open the valve, a plunger extending through the gasoline tank and having the lower end thereof loosely received within the socket of the push rod, and means for actuating the plunger.

4. In a gasoline cut-off for internal combustion engines, the combination of a gasoline tank having a sediment bulb at the bottom thereof, a feed pipe leading from 130

the sediment bulb, a valve mounted within the sediment bulb for controlling the feed pipe, a guide rod projecting upwardly from the bottom of the sediment bulb, a slide 5 mounted upon the guide rod and having an operative connection with the valve, a spring surrounding the guide rod and engaging the slide to hold the valve normally in a closed position, a push rod provided 10 at its upper end with a socket and at its lower end with a cage loosely engaging the guide rod, said push rod being adapted

to engage the slide to move the same against the action of the spring and open the valve, a plunger extending through the tank and 15 having the lower edge thereof loosely received within the socket of the push rod, and means for actuating the plunger.

In testimony whereof I affix my signature in presence of two witnesses.

WILLIAM OTHO REID.
